CENTRIFUGAL PUMP

Filed Oct. 7, 1932

UNITED STATES PATENT OFFICE

2,007,126

CENTRIFUGAL PUMP

Charles E. Koons, High Bridge, N. J., assignor
to Taylor-Wharton Iron and Steel Company,
High Bridge, N. J., a corporation of New Jersey

Application October 7, 1932, Serial No. 636,744

1 Claim. (Cl. 103—115)

The invention chiefly is concerned with the problem of pumping water and other fluids containing solid matter in suspension and provides certain improvements in the rotors or impellers of centrifugal pumps to the end of accelerating flow by eliminating or minimizing conditions, the presence of which makes for obstruction, choking action and other friction forces tending to retard flow and tending to rapid and destructive wear.

Otherwise stated, the invention is embodied in an impeller having certain novel and useful characteristics whereby the output of the pump is considerably increased and whereby the wear on the vanes, back shroud, and pump casing is considerably reduced.

One embodiment of the invention is illustrated in the accompanying drawing forming a part hereof, wherein

Figure 1 is a central vertical section of the improved pump.

Fig. 2 is a section on line 2—2 of Fig. 1.

Fig. 3 is a section through the casing to show the rotor in plan; and

Fig. 4 is a section on line 4—4 of Fig. 1.

For the sake of clearness the end plates on the suction and engine sides, 6 and 7, respectively, of the pump casing 5 have been omitted, but it will be understood that such plates are a complement of the casing in accordance with the usual practice.

The rotor or impeller 8 has a hub 9 whereby it is mounted for rotation on a shaft 10.

Heretofore, it has been the practice to equip impellers with vanes having flat driving or propelling faces, the effect of which was that, under operating conditions, the material tended to crowd the engine side of the casing thereby preventing a free discharge and causing the pump to clog or choke.

I depart from this practice and provide an impeller so constructed as to force the material to the center of the pump, rather than have it crowd the engine side, thereby providing for free discharge and reducing wear on the parts.

According to my invention the rotor is a unit casting embodying a pair of spaced disks of which one, as before indicated, is equipped for rotative mounting, and of which the other, 11, is of general ring form, there being a central opening 12 directed towards the suction side of the pump casting. The rotor disks have impeller characteristics conferred upon them by a series of intermediate tying webs in the form of curved radially disposed vanes or flukes 13 springing from the main or hub-carrying casting and themselves carrying the other disk or suction ring. The vanes or impeller elements 13 are, in contradistinction with the old practice, of concave form well defined throughout their entire lengths. Otherwise stated, they are of general scoop form as indicated at 14 developed by a concavo-convexo construction of web.

Having described the invention, what I claim is:—

A pump impeller including spaced disks, one being solid and the other formed with a suction opening, a hub mounting formed as an integral part of the solid disk, and webs arranged wholly inwardly of the hub mounting and bridging the suction opening, the webs being in a plane at right angles to the axis of the hub mounting and being concaved transversely and curved longitudinally, the opposing edges of the webs being integral with the respective disks and forming the sole support of the disk having the suction opening.

CHARLES E. KOONS.
